UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

LOOM-CONTROLLING MECHANISM.

1,240,375.

Specification of Letters Patent. Patented Sept. 18, 1917.

Application filed February 1, 1917. Serial No. 146,027.

To all whom it may concern:

Be it known that I, EPPA H. RYON, a citizen of the United States, residing at Waltham, in the county of Middlesex and State of Massachusetts, have invented a new and useful Loom-Controlling Mechanism, of which the following is a specification.

This invention relates to loom controlling mechanism of the type in which indicator levers or other corresponding elements are actuated and controlled by the coöperative action of a plurality of pattern cylinders.

Such a mechanism is shown in my prior Patent No. 1,179,423 issued April 18, 1916, and my present invention relates to certain improvements in the loom controlling mechanism or multiplier therein shown.

It is the object of my present invention to provide a mechanism of this type which is particularly adapted for weaving blankets or other fabrics in which two weaves are found, one weave commonly forming the body portion of the fabric, and the other weave being used for the border or heading of the separate articles successively woven in the fabric. For the attainment of this object I provide two actuating cylinders which jointly control and actuate the indicator levers through which the drop boxes or other loom mechanism is controlled. These actuating cylinders are operated independently of each other, and neither cylinder is in any way controlled by the other cylinder.

In addition to the actuating cylinders I provide two multiplying cylinders each of which may be put in operation by either actuating cylinder. A multiplying cylinder thus put in operation, after completing one run of its multiplying chain or pattern, will always restore control of the mechanism to the particular actuating cylinder by which the multiplying cylinder was started.

In addition to the actuating and multiplying cylinders above described, I also provide a control cylinder effective to determine which actuating cylinder shall operate, thus governing the sequence of the weaves in the fabric. This control cylinder may also be used as a multiplier to cause a repetition of the entire pattern carried by either actuating cylinder.

While the broad features of my invention have been set forth above, my invention also consists in certain arrangements and com-

bination of parts which will be hereinafter described and more particularly pointed out in the appended claims.

The preferred form of my invention is shown in the drawings in which—

Figure 1 is a plan view of my improved controlling mechanism or multiplier;

Fig. 2 is a sectional side elevation taken along the line 2—2 in Fig. 1;

Fig. 3 is a similar sectional elevation taken along the line 3—3 in Fig. 1, and

Fig. 4 is a diagrammatic plan view of the different pattern cylinders.

Referring to the drawings, the controlling or multiplying mechanism is mounted in side frames 10 and 11 connected by horizontal members or cross girts 12 (Fig. 2) to an upright stand 13 by which the mechanism may be secured to the loom frame. The side frame members 10 and 11 are also connected to each other by cross rods 14, 15, 16, 17 and 18 (Fig. 2) to which the members are secured by set screws 19 (Fig. 1).

In the frame work thus constructed I mount five pattern cylinders A, B, C, D, and E. The cylinders A and B are termed the actuating cylinders as they directly control the operation of the indicator levers 20 and 21 which in turn control the drop boxes or other loom mechanism connected thereto. The levers 20 and 21 overlie the actuating cylinder A and are directly operated by pattern rolls thereon. The levers 20 and 21 are provided with extensions 20^a and 21^a, said levers and extensions being rigidly connected through intermediate portions 20^b and 21^b, each lever, extension and intermediate portion forming a single pivoted structure loosely mounted upon the cross rod 14. The extensions 20^a and 21^a overlie the actuating cylinder B and are operated by pattern rolls thereon.

The cylinder A is fixed to a shaft 22 (Fig. 2) having a bearing in the member 10 of the multiplier frame. A hand wheel 23 secured to the shaft outside of the side frame 10 provides means for manually setting the cylinder A. The actuating cylinder B is freely rotatable upon the shaft 22 and is provided with a cylindrical extension 100 on its outer side which has a bearing in the side frame 11. A hand wheel 24 secured to the cylindrical extension outside of the frame 11 provides for the manual setting of the cylinder B.

The cylinders C and D I term multiplying cylinders as their sole function is to cause a definite number of repetitions of a particular combination in the pattern on 5 one or the other of the actuating cylinders A and B. The cylinder C is fixed to a shaft 25 and the cylinder D is rotatably mounted upon said shaft, the construction being exactly similar to that already described in 10 connection with the cylinders A and B. Hand wheels 26 and 27 are provided for manual adjustment of the cylinders.

The control cylinder E determines which actuating cylinder A or B shall become or 15 continue operative. This cylinder is rotatably mounted upon the cross rod 17 previously described.

For advancing the cylinders I provide feed pawls 30, 40, 50, 60 and 70 (Figs. 1 and 20 3), these pawls being all pivotally mounted upon an oscillating arm 28 loose on a short horizontal shaft 29 secured in bearings in the stand 13 and the side frame 11. An actuating arm 29^a (Fig. 1) is movable with the 25 arm 28 and is suitably connected to any convenient part of the loom from which motion may be derived in timed relation to the movement of the lay. The arm 28 makes one complete oscillation for each beat of 30 the lay.

The feed pawls 30, 40, 50, 60 and 70 cooperate with ratchet wheels 31, 41, 51, 61 and 71 connected to and rotatable with the pattern cylinders A, B, C, D and E. Locking disks 32, 42, 52, 62 and 72 are mounted to rotate with the corresponding ratchet wheels and are each provided with a series of concave peripheral portions corresponding in number to the number of sprocket teeth on 40 the different pattern cylinders. Locking levers 33, 43, 53, 63 and 73 yieldingly engage the different locking disks. The levers 33 and 43 are connected by a tension spring 330 (Fig. 3) and the levers 53 and 63 are similarly connected by a tension spring 530. A spring 730 (Fig. 1) provides similar spring tension for the lever 73.

As the feed pawls are continuously oscillated the operation of the different cylinders is controlled by means of shields 34, 44, 54, 64 and 74 which underlie lateral projections on the feed pawls. When a shield is raised the corresponding feed pawl is inoperative. The pawls 34, 44, 54 and 64 are 55 each formed integrally with rockers 35, 45, 55 and 65 (Figs. 1 and 3). These rockers are mounted in pairs, the rockers 35 and 45 being pivoted upon the cross rod 15, and the rockers 55 and 65 being similarly supported 60 upon the cross rod 16. Each rocker 35 and 45 is provided with three arms or projections numbered 36 and 46 respectively. In the outer end of each arm an adjusting screw is provided for engagement by a weighted control lever (to be described). The rockers 55

and 65 are each similarly provided with two projecting arms marked 56 and 66 respectively and by which they are similarly controlled.

The shield 74 for the cylinder E is secured 70 to a rocker in the form of a rock shaft 75 rotatable in bearings in the side frames 10 and 11. Projecting arms 76 are secured to the outer ends of the shaft 75, these arms projecting toward the center of the multiplier and being provided with adjusting screws in the same manner as the projections 36, etc., previously described. A pair of auxiliary shields 540 and 640 are also fixed 75 to the shaft 75 and form an auxiliary control (to be described) for the feed pawls 50 and 60. Counterweights 76^a are provided to counterbalance the weight of the shields 540 and 640, and of the pawls 50 and 60 at times supported thereby.

I will now describe the devices for controlling the shields 34, 44, 54, 64 and 74. In Fig. 4 I have indicated the five pattern cylinders and the different series of pattern rolls which are mounted thereon. Each of 90 the actuating cylinders A and B has five parallel series of pattern rolls. The multiplying cylinders C and D each have a single series of rolls, and the control cylinder E has a double series of rolls.

On the cylinder A the rolls *a*—*a* control the indicator levers 20 and 21; the rolls *a'* control the multiplying cylinder D; the rolls *a*² control the multiplying cylinder C; and the rolls *a*³ govern the control cylinder E. 100 Similarly on the cylinder B, the rolls *b*—*b* engage the extensions 20^a and 21^a of the indicator levers 20 and 21; the rolls *b'* control the multiplying cylinder D; the rolls *b*² control the cylinder C; and the rolls *b*³ control 105 the cylinder E. On the cylinder C, the single series of rolls *c* controls both actuating cylinders A and B, and on the multiplying cylinders D the single series of rolls *d* similarly controls both actuating cylinders A 110 and B. On the cylinder E the rolls *e* control the cylinder A, and the rolls *e'* control the cylinder B.

The control connection from the different series of pattern rolls to the different feed 115 pawl shields is made through weighted levers which normally rest upon the projecting arms of the rockers 35, 45, 55 and 65 or of the rock shaft 75 and which are raised from said arms by the placing of pattern 120 rolls under the levers. Referring to Fig. 1, three weighted levers 67, 57 and 77 overlie the pattern rolls *a'*, *a*² and *a*³ of the cylinder A, these levers respectively controlling the feed of the cylinders D, C and E. Similar 125 levers 67^b, 57^b and 77^b overlie the rolls *b'*, *b*² and *b*³ of the cylinder B respectively, and control the feed of the cylinders D, C and E. Two weighted levers 37 and 47 overlie 130 the rolls *e* and *e'* of the control cylinder E,

these levers engaging arms 36 and 46 respectively on the rockers 35 and 45 and thus controlling the feed of the actuating cylinders A and B. A single lever 370 overlies 5 the roll *d* of the multiplying cylinder D, but this lever is formed with its weighted end of double width so that it engages two projections 36 and 46, and thus controls the feed of both cylinders A and B. A similar lever 10 470 overlies the rolls *c* of the multiplying cylinder C and also controls the feed of the two actuating cylinders A and B.

Having described the construction of my improved controlling mechanism or multi- 15 plier, I will now point out its method of operation. In Fig. 1 I have shown the rolls on the several pattern cylinders in such a position that the cylinders B, D and E are inoperative and the cylinder C is about to 20 multiply the combination called for by the cylinder A. It will be noted that the cylinder B is stopped with rolls *b'*, *b²* and *b³* underlying the weighted levers 67^b, 57^b and 77^b. The rockers 55, 65 and the rock shaft 25 75 are thus released by the cylinder B, and the shields 54, 64 and 74 for the cylinders C, D and E are free to drop, so far as the weighted levers actuated by the cylinder B are concerned. It will also be noted that no 30 roll *b* is operatively positioned, so that the indicator levers 20 and 21 can be freely raised or lowered by the rolls *a* on the cylinder A. This combination of rolls is always used on the cylinder A or B at the point at 35 which the pattern is completed and the control is to be shifted to the other actuating cylinder.

This shifting of the control is determined by the cylinder E which is shown in Fig. 40 1 as having a roll *e* under the lever 37, thus releasing the feed pawl 30 for the cylinder A, while the absence of a roll *e'* under the lever 47 permits this lever to rest upon an arm 46 and thus raise the shield 44 to render 45 the feed pawl 40 inoperative.

On the cylinder A the rolls *a* may be placed as desired to give the desired movements to the indicator levers 20 and 21. In the position shown in the drawings, a roll 50 *a* underlies the lever 20 which is raised there- 55 by. A roll *a²* also underlies the lever 57, raising the lever from one of the projections 56 of the rocker 55 which controls the feed of the multiplying cylinder C. As the lever 57^b controlled by the cylinder B is also raised, the shield 54 will fall and the cylinder C will be started at the next movement of the actuating arm 29^a. The first advance movement of the cylinder C will remove the 60 roll *c* from beneath the lever 470 and this lever will then rest upon projections 36 and 46 of the rockers 35 and 45, thus holding both feed pawls 30 and 40 out of operation until the cylinder has completed its series.

65 Each multiplying chain is formed of a

single pattern roll and any desired number of blanks connected by the necessary links. For instance, the cylinder C may have a chain of twenty links and the cylinder D may have a chain of ten links, each chain 70 having a single roll *c* or *d*. When the roll *c* returns to operative position it will raise the lever 470, releasing the pawls 30 and 40. The pawl 40 will be still held from operation by the lever 47 controlled by the cylinder E, but the pawl 30 will be free to feed the cylinder A forward one step.

In the combination shown in the drawing, the next movement of the chain upon the cylinder A will place the rolls *a'*, *a²* and *a³* 80 under the levers 67, 57 and 77, and will omit rolls *a* under the indicator levers. All of the weighted levers which control the cylinders C, D and E are therefore raised, and all of the feed pawls 50, 60 and 70 would 85 become simultaneously operative if it were not for the auxiliary shields 540 and 640. As the levers 77 and 77^b are raised from the arms 76, the counterweights 76^a will move the rock shaft 75, raising the auxiliary 90 shields 540 and 640 and depressing the shield 74. The pawls 50 and 60 are thus rendered inoperative by the auxiliary shields, and the pawl 70 is alone operative to advance the cylinder E. Such advance movement in the 95 direction of the arrow will remove the roll *e* from beneath the lever 37 and will cause a roll *e'* to raise the lever 47. The lever 37 will render the pawl 30 and cylinder A inoperative, and the raising of the lever 47 100 will permit the pawl 40 to actuate the cylinder B. Upon the next forward movement of the cylinder B a roll *b'* will raise the lever 67, thus releasing the pawl 60 and causing the multiplying cylinder D to operate.

It will be noted that the multiplying cylinders always stop with rolls under the levers 370 and 470, thus leaving the pawls 30 and 40 under the control of the cylinder E. While I have described the advance move- 110 ment of the cylinder E as shifting the control from the cylinder A to the cylinder B it will be evident that a roll *e* instead of the roll *e'* might have been placed in the next link of the chain and that a roll *e* thus positioned would have again released the feed pawl 30, in which event the cylinder A would have repeated its series of combinations.

Having thus described my invention it will be evident that changes and modifications can be made therein by those skilled in the art without departing from the spirit and scope thereof as set forth in the claims, and I do not wish to be otherwise limited to the details herein disclosed, but what I claim 125 is:

1. Loom controlling mechanism having, in combination, a pair of actuating cylinders, two multiplying cylinders for said actuating cylinders, a control cylinder for said 130

actuating cylinders, and pattern-controlled means to feed each cylinder.

2. Loom controlling mechanism having, in combination, a pair of actuating cylinders each controlled and rendered operative independently of the other, two multiplying cylinders each controlled and rendered operative independently of the other by either of said actuating cylinders, a control cylinder determining the operation of said actuating cylinders, and pattern-controlled means to feed each cylinder.

3. Loom controlling mechanism having, in combination, a pair of actuating cylinders, two multiplying cylinders for said actuating cylinders, a control cylinder for said actuating cylinders, and pattern-controlled means to feed said cylinder, said multiplying cylinders being each controlled directly from each of said actuating cylinders and being rendered inoperative whenever the control cylinder is rendered operative.

4. Loom controlling mechanism having, in combination, a pair of actuating cylinders, two multiplying cylinders for said actuating cylinders, a control cylinder for said actuating cylinders, means to feed each cylinder, and devices to render the feed of the multiplying cylinders inoperative whenever the feed of the control cylinder is operative.

5. Loom controlling mechanism having, in combination, a pair of actuating cylinders, two multiplying cylinders for said actuating cylinders, a control cylinder for said actuating cylinders, indicator levers jointly controlled by said actuating cylinders, a separate set of control levers operated by each actuating cylinder, each set being effective to determine the operation of the multiplying cylinders and the control cylinder, and means to feed said cylinders.

6. Loom controlling mechanism having, in combination, two actuating cylinders, two multiplying cylinders, means to feed each cylinder, and means to control the feed of each cylinder, including a single weighted lever for each multiplying cylinder, each lever when lowered being effective to render the feed of both actuating cylinders inoperative.

7. Loom controlling mechanism having, in combination, two actuating cylinders, two multiplying cylinders, means to feed each cylinder, and means to control the feed of each cylinder, each actuating cylinder feed being controlled independently of the

other actuating cylinder, each actuating cylinder controlling the feed of both multiplying cylinders, and a single control lever for each multiplying cylinder being effective when lowered to render both actuating cylinders inoperative.

8. Loom controlling mechanism having, in combination, a pair of actuating cylinders, two multiplying cylinders for said actuating cylinders, a control cylinder for said actuating cylinders, indicator levers controlled jointly by said actuating cylinders, separate weighted levers operated by each actuating cylinder to jointly control said multiplying cylinders and said control cylinder, and a single weighted lever operated by each multiplying cylinder and itself controlling both actuating cylinders.

9. Loom controlling mechanism having, in combination, a pair of actuating cylinders, two multiplying cylinders for said actuating cylinders, a control cylinder for said actuating cylinders, feed pawls for said cylinders, shields for said pawls, rockers for said shields, and weighted levers controlling said rockers, each actuating cylinder having a separate weighted lever for each multiplying cylinder rocker and for the control cylinder rocker, each multiplying cylinder having a single weighted lever controlling both actuating cylinder rockers, and the control cylinder having a separate weighted lever for each actuating cylinder rocker.

10. Loom controlling mechanism having, in combination, a pair of actuating cylinders, two multiplying cylinders for said actuating cylinders, a control cylinder for said actuating cylinders, feed pawls for said cylinders, shields for said pawls, rockers for said shields, weighted levers controlling said rockers, and supplementary shields on the control cylinder rocker effective to render the multiplying cylinder feed pawls inoperative whenever the control cylinder feed pawl is operative.

11. Loom controlling mechanism having, in combination, a pair of actuating cylinders, two multiplying cylinders for said actuating cylinders, a control cylinder for said actuating cylinders, pattern-controlled means to operate each cylinder including an oscillating driving member, and separate pawls on said member for feeding each of said cylinders.

In testimony whereof I have hereunto affixed my signature.

EPPO H. RYON.
